HIGH PRESSURE GAS MAKING PROCESS

Otto Hubmann, Frankfort-on-the-Main, Germany, assignor to American Lurgi Corporation, New York, N. Y., a corporation of New York

Application February 27, 1931, Serial No. 518,834
In Germany March 10, 1930

14 Claims. (Cl. 48—202)

This invention relates to a process for the production of gas of high calorific power, and by-products, by gasification with oxygen under elevated pressure.

For the production of a high-power gas—that is to say, a gas of higher calorific power than ordinary producer gas—it has recently been proposed to effect the gasification by means of oxygen, followed by improving the crude gas by effecting catalytic formation of hydrocarbons and washing out the inert carbon dioxide. For remote supply, this gas must be compressed to the requisite pressure after purification to remove sulphuretted hydrogen and the like, unless such compression has been effected prior to the improving treatment. The production of high-power gas in this manner, however, is attended with technical and economic difficulties which are mainly attributable to the existing inadequate output capacity of the proposed apparatus and processes, the cost of the necessary oxygen, the expense of compressing large volumes of gas, and the difficulty of controlling the temperature conditions in the bed of fuel, so that, up to the present, nothing is known with regard to the carrying out of these proposals on a technical scale.

In order to obviate these difficulties, the process of the present invention gasifies the fuel with oxygen, or air enriched with oxygen, and abundant quantities of steam, under elevated pressure. In special cases carbon dioxide may be added to the oxygen, in addition to, or instead of, steam.

Types of gas producers, designated high-pressure producers, are known, but, unlike the invention, these do not work with a pressure of several atmospheres. On the contrary, they serve for the gasification of small coal with blast pressures up to about 700 mm. water-gauge. The positive pressure is mainly applied for the purpose of penetrating through the column of coal in the producer, and the resulting gas is of the ordinary pressure. Although recent proposals refer to the pressure gasification of semi-coke with steam, this process is attended with difficulties which cannot be overcome by the means at present available in the art, since it is essential, for the continuous performance of the endothermic water-gas reaction, to supply heat, the provision of which, by superheating the high-pressure

steam to temperatures exceeding 600° C. is technically impracticable.

It has also been proposed to perform the gasification process, at the highest practicable temperatures, with dry air, or air with the smallest possible addition of steam, as gasifying agent, and under such increased pressure that the influence of pressure and high temperature produces extensive cracking of the tar contained in the fuel, and converts it into gaseous hydrocarbons. By this means, the calorific power of the gas is slightly increased and the formation of condensable constituents, such as tar, oil, and the like, prevented.

For remote or urban gas supply, however, the latter process cannot be considered, since neither the calorific power nor the composition of the gas, nor, in particular, its specific gravity, or content of hydrogen and carbon monoxide, are sufficient for these purposes.

On the other hand, a gas of very high-grade quality and rich in methane and hydrogen is obtained by gasification, under elevated pressure, with oxygen, or air enriched with oxygen, and a copious addition of steam, in accordance with the present invention. The process of the invention operates, for example, in the following manner:

The gasifying medium admitted into the producer consists of oxygen under pressure, to which, according to the invention and contrary to the usual practice, steam is added in such quantities as thereby to lower the reaction temperature in such a manner that, apart from the production of a gas which is, above everything, low in carbon monoxide, the difficulties with regard to the structural material of the gasification shaft and the clinkering of the gasification residue are entirely obviated. Moreover, the said steam can be supplied at a superheat of about 450° C., which is easily attained in practice. The admission pressure of the gasifying medium can be sufficiently high to obviate the necessity for compressing the resulting gas any further for the purpose of remote supply and purification (such as washing out the carbon dioxide). No compression is needed, both the steam and oxygen required for the gasification being obtainable, without any considerably increased expense, under the pressure at which they are employed according to the invention. On the other hand, in all the existing

processes furnishing gas for transmission to remote points, i. e., 10 to 100 or more kilometers from the source of supply, the resulting gas—the volume of which is 5-6 times that of the oxygen employed as gasifying agent—must be compressed—before or after purification—to the requisite degree. Economical gasification with oxygen has, for the first time, been rendered possible by the economy which the new process effects by dispensing with compression.

The reaction under high pressure has a further advantageous effect in that it is attended with a substantial increase in the throughput. For a given grain-size of fuel, the production of dust and the risk of local eruptions of gas in the producer is known to be proportional to the square of the velocity, and directly proportional to the specific gravity of the gasifying agent, and therefore with increasing gasification pressure, (in contrast to the usual gasification under approximately atmospheric pressure), the cross-sectional load can also be increased in proportion with the square root of said pressure, so that—quite irrespective of the increased output already rendered possible through gasification with oxygen—the throughput of fuel can also be increased, for example by about 3.8-fold in the case of gasification under a pressure of 15 atmospheres.

In the process of the present invention, the application of high pressure in conjunction with an increased proportion of steam, also produces a considerable improvement in the high-power gas, through the formation of hydrocarbon compounds ($\text{CH}_4, \text{C}_2\text{H}_6$ and the like), as the result of the hydrogenating action of the resulting hydrogen on the fuel. With regard to the general course of the gas reaction, it is known that rising temperatures facilitate the decomposition of compounds of high molecular weight in the direction of the hydrogen side of the reaction equation. Increased pressure, on the other hand, leads to the system with small volume, that is to say, in this case, to the formation of hydrocarbon compounds by hydrogenation with the free hydrogen. Experiment has demonstrated that it is possible—especially in the case of geologically more recent fuels like peat and lignite—by operating in this manner, to carry out a continuous gasification process at temperatures of 600-700° C., so that low temperatures and high pressure already influence the course of the reaction in the gas producer in the direction of the formation of the desired hydrocarbons. Moreover, the reaction may be substantially accelerated by adding catalytically active substances to the fuel. A particularly advantageous feature, however, is that the formation of carbon monoxide is lessened, by the low gasification temperature and the effect of the high pressure, in favour of the formation of carbon dioxide, so that the final gas contains considerably less carbon monoxide than other gases produced by gasification, for instance, normal water gas, while the inert carbon dioxide can be easily removed by the aid of known methods. This is the more feasible inasmuch as the gas blown in accordance with the present invention is produced with the pressure needed for the process of eliminating carbon dioxide, and the compression otherwise required is therefore superfluous. At the same time, the amount of oxygen needed per cubic metre of gas produced, decreases as the pressure increases.

With the process as described it is possible

to gasify bituminous fuel as well as anthracite and coke completely with conversion of 80% to 90% of the calories contained in the fuel into a gas of more than 565 B. t. u. per cubic foot. Working under a pressure of 25 atmospheres anthracite coal with 6% volatiles has been completely gasified in continuous operation to a gas of the following composition:

	Percent	10
CO	11.7	
H ₂	37.7	
CH ₄	14.3	
C _n H _m	0.3	
N ₂	1.0	
CO ₂	35.0	15

After elimination of carbon dioxide this gas consists of

	Percent	20
CO	18	
H ₂	58	
CH ₄	22	
C _n H _m	0.5	
N ₂	1.5	

and corresponds to coal gas in point of density, calorific power and low content of carbon monoxide.

The gas furnished by the process of the present invention can be subjected direct to any convenient additional processes for purification and improvement, the performance of which processes is substantially facilitated and accelerated by the pressure already existing. This applies, in general, as regards the elimination of condensable or gaseous constituents, whether by compression followed by supercooling, or by adsorption or chemical combination with the aid of solid or liquid substances, and also as regards the performance of reactions in which conversions are effected by catalytic action. By gasification under elevated pressure, the present process enables even inferior fuels—such as brown-coal—to be converted into a high-power gas corresponding to coal gas in point of density, calorific power and low content of carbon monoxide.

Pulverulent fuels can be treated, with special advantage, by the process of the present invention. The employment of dusty and fine-grain fuels considerably facilitates the introduction of the charge into the reaction chamber which is under pressure, and also the removal of the residues, which remain in a pulverulent condition owing to the low gasification temperature of the process. Naturally, in such case the gasifying reaction does not take place in a stationary bed of fuel, the fuel dust being, on the contrary, fed towards the ascending reaction gas in known manner, and preferably in a state of agitation.

In such event, the process according to the present invention is carried out, for example, in that the dust to be gasified is allowed to trickle down through (for example) a brick-lined vertical or inclined shaft, whilst the gasifying medium is introduced, under high pressure, at the bottom of the shaft, and ascends to meet the dust. In this manner, the dust is kept in a state of suspension—for example by introducing the gasifying medium tangentially—for some time, in known manner, and converted into gas.

Another embodiment of the invention consists in introducing the gasifying medium and dust, in the same direction, into the bottom of the reaction apparatus, the upper portion of which, however, is conically widened, so that, through

the reduced velocity of the gas, the dust is, at least partially, separated from the current of gas.

In this case, the gasification residue can be removed by interrupting the admission of the 5 gasifying medium for a few seconds, at intervals of (for example) 5 minutes, so that the residue can fall down through the narrow zone. Under these conditions there is no need to reduce the pressure in the gasification chamber.

10 In order to increase the hydrogenating action of the hydrogen formed in the gasification process, a hydrogenation zone may be disposed in front of the gasification zone, so as to enable the liberated hydrogen to act for some time on the fuel before the latter is gasified. The gases containing the hydrogen can pass directly from the gasification zone into the superimposed hydrogenation zone, while the fuel gradually sinks down through the gasification zone. The 15 heat necessary for hydrogenation is furnished, for the most part, by the ascending gas itself. However, since the hydrogenation reaction is greatly accelerated by accurately regulating its temperature, the hydrogenation zone can be 20 specially provided with additional heat, for example, in known manner, by radiators traversing the hydrogenation zone and heated either by gas or by electrical heating resistances. In the case of suitable fuels, the fuel itself may also act as 25 the resistance for the electric current, and thus serve as a heating agent. The fuel itself is preferably raised to the high temperature required for the time being, before it enters the hydrogenation zone.

30 The pressure under which the gasification proceeds need not, of course, correspond to that in the distribution mains. Thus, in some cases, it may be preferable to gasify under a higher pressure, if this enables a high-power gas to be produced which will have the desired composition after the carbon dioxide has been washed out. The surplus pressure energy can then be utilized, to advantage, for driving the auxiliary machines required for carrying out the process. Conversely—taking the process, as a whole, into consideration—the pressure in the gas producer may be 35 kept somewhat lower than is needed for the further application of the gas, and may be increased, by stages, directly after, or between, the several 40 operations of purification and improvement.

45 The arrangements for charging and emptying a gas producer operating in accordance with the process of the present invention must, naturally, be designed in accordance with special points of view. In the existing methods of gasification under ordinary pressure, the gas producer was mostly provided with a double seal hopper through which the fuel was introduced into the 50 gasification chamber. In gasifying fuels under pressure, however, the sealing appliances have, in contrast to all those hitherto known, to be maintained gas-tight against an extremely high pressure and are subjected to heavy wear. When they are being opened, the pressure balance between the several chambers occurs with a very 55 rapid flow of gas, and the fuel carried in the gas current abrades the jointing surfaces, in particular, very extensively. Moreover, it is essential that losses of gas while charging should be prevented as far as is possible.

60 According to the present invention, these difficulties are obviated by the provision of a charging lock, into which the fuel is introduced, the chamber being then closed and the internal pressure raised to that of the gasification chamber

65 by means of the surplus carbon dioxide from the process itself, and/or by steam, or similar means. The fuel is then transferred from the lock to the gasifier, and communication between the lock and gasifier is again interrupted, for the purpose 70 of introducing a fresh charge. For very moist fuels, the charging lock can also be designed in such a manner that the fuel can be dried therein, in known manner, by the direct introduction of high-pressure steam. Similarly, the discharge of 75 the gasification residue can be effected with the aid of a lock, or by flushing. The gas producer itself is designed, in the usual manner, as a lined cylindrical shaft, with or without mechanical ash-handling appliances, and, notwithstanding 80 the high pressure, is of relatively large cross section, since, owing to the lower gasification temperatures employed, the stresses to which the shell of the producer is exposed, can be kept within technically controllable limits. Moreover, the shell can, without difficulty, be cooled 85 by water or air.

90 The gas producer may also be charged by forcing the coal in, through a suitably tapered moulding channel, under a considerably higher pressure than that of the gasification chamber, in such a manner that the fuel pressed into said channel forms a seal between the internal pressure of the producer and that of the outside air.

95 For example, a brown-coal briquetting press 30 (not shown) of known type may be used. The gas-tight moulding channel of this press terminates in a section of pipe corresponding with the shape of the briquette and discharging into the high-pressure gas producer. The crumbly or fine-grained coal is placed in the charging hopper of the briquette press and forced by the press ram into the moulding channel. The bends in the channel are gradually tapered so as to set up a high frictional resistance, sufficient to produce 40 blocks of adequate tenacity and enable the "plugs" thus formed to stand the internal pressure. The charging hopper of the press is preferably closed by a self-acting lock, operating under a low (approximately atmospheric) pressure, to protect the 45 operators against any gas that may possibly issue through the moulding channel of the press. Moreover, the gases are preferably evacuated from the charging hopper, so as to prevent them 50 from inconveniencing the operators in any circumstances.

100 For gas-producer plants comprising a plurality of producers, it has also been recognized as particularly advantageous for the charging and ash removal of the several producers to be effected through lock appliances common to all, and the charge introduced into each only after being locked in the pressure chamber. In addition to reducing the expenditure in material and manual labour, this method obviates, in a practically complete manner, the possibility of the process being jeopardized through faulty attention and through leakage at the seals. In certain cases it is also advisable to employ lock chambers of greater capacity than usual and capable, for 65 example, of containing sufficient fuel for a prolonged working period. Moreover, two (for example) of these larger charging appliances may be provided, which are placed in communication, at intervals, with the pressure chambers of the 70 gas producers, preferably by means of an interposed special conveyor device, such as a worm (not shown) which distributes the fuel to the various points of utilization. Naturally, in this case also, the fuel can be introduced into the 75

distributing chamber for the various producers by means of a press instead of a lock.

In order more clearly to understand the invention, reference is made to the accompanying drawings which illustrate diagrammatically and by way of example typical forms of apparatus for carrying out the process, according to the invention.

Fig. 1 is a representation of several gas producers, combined into a plant with common charging and residue-handling appliances.

Fig. 2 represents an apparatus suitable for hydrogenation at the same time.

The gas producers 1, 2 and 3 have a common charging appliance, consisting of the lock chamber 4, adapted to be hermetically closed at the top by a cover 5. The lock chamber houses the (also gas-tight) seal 6, consisting of a cone 6a, which is adapted to be raised and lowered by means of rods 6b and counterweight 6c, and is pressed in a gas-tight manner against the seating surface of the interior member 6d directly the pressure in the lower portion of the lock chamber exceeds that in the upper portion. Charging pipes 14 lead from the bottom of the lock chamber to the several producers. These pipes 14 may be provided with valves (not shown) serving to regulate the distribution of the coal to the several producers in the desired manner. The pipe 10 leads from one of the supply pipes 14, or from a producer, into the upper portion of the lock chamber, from which latter, gas can be led away through the exhaust pipe 11. The pipes 10 and 11 are provided with stop-valves 10a, or 11a. The gas producers, which consists of a shell of strong material, such as steel, and a lining 17 of refractory material, are supplied with the gasifying agent through the pipes 12, and the gas produced is led away through the pipes 13. 18 The discharge openings 19 are the discharge openings from the producers, and are succeeded by conveyor devices, such as worms 7, which transport the gasification residues into the pipes 19 leading to the discharging apparatus, which is arranged in the same manner as the charging device. It consists of a lock chamber 15, which is closed below by the gas-tight cover 9, and is divided into an upper and a lower chamber by a member 8, which also closes in a gas-tight manner. The member 8 may be designed in the same way as the member 6 of the charging device, that is to say, may consist of a cone 8a, fitting gas-tight into the member 8d and being raised and lowered by means of rods 8b and counterweight 8c. The gas-tight seal between the surface of the cone and the seating surface of the member 8d must, however in this case, be effected under a correspondingly high pressure, produced, for example, by hydraulic means. A gas pipe 20 connects the lower portion of the lock chamber 8 with the producer, or the discharge pipe 19, whilst another pipe 21 serves to lead the gas out of the lower chamber of the lock. Both pipes are fitted with stop-valves 20a and 21a.

For the purpose of admitting the fuel into the lock 6, the gas in the upper portion of the lock chamber is first evacuated through the pipe 11, until the pressure in the upper portion of said chamber is approximately atmospheric. The upper portion of the chamber will then become shut off, gas-tight, from the lower portion by the cone 6a and the member 6d, whereupon the cover 5 is opened and fuel is admitted into the upper portion of the lock chamber. After this portion has been reclosed by the cover 5, the valve 10a in the gas pipe 10 is opened and the upper portion of

the lock chamber is exposed to the pressure which obtains in the gas producers. The cone 6a may now be lowered, so that the fuel drops out of the upper portion of the chamber into the lower, from which it is distributed to the several producers by way of the pipes 14, and is gasified. The gasification is effected by admitting a mixture of oxygen and steam through the supply pipe 12, the free space existing below the shoulder 22 on the lining assuring better distribution of the gasifying medium in the producer.

The gasifying medium, which may consist, for example, of 1 part by volume of oxygen to 6-10 parts by volume of steam, is introduced under a pressure of about 20-50 atmospheres. The resulting gas, which issues from the producers through the pipe 13, is under approximately the same pressure. The gasification residues pass from the discharge openings 18, through the worms 7 and into the upper portion of the lock chamber 15, where they accumulate above the cone. If the lock chamber has become sufficiently full, the cone is lowered so that the residues drop into the lower portion of the chamber. After the cone 6a has been lifted and a gas-tight seal has been established between the lower and upper portions of the lock chamber, the pressure in the lower portion is relieved, the cover 9 is opened, and the residues in the said lower portion are discharged. After the lower portion of the lock chamber has been reclosed and placed under sufficient pressure by admitting gas through the pipe 20, a further batch of gasification residues can be discharged in the same manner. Hence, by means of this, or some analogous design of the charging and discharging apparatus, the gasification can be performed in a continuous manner without any working difficulties, and, inasmuch as the same charging and discharging apparatus can be employed for a series of producers, the operation is also comparatively simple.

If, in special cases, very high pressures are to be employed, intermittent gasification may be preferred to this continuous operation. For this purpose, the pressure in the gasification chamber is relieved when the reaction has terminated, the residue is evacuated, and the chamber is recharged with fuel. Under these conditions, the provision of special locks may be omitted.

If the gasification is to be accompanied by the hydrogenating action of the hydrogen, or the like, contained in the resulting gases, on the fuel from which the volatile constituents or a large portion of the same have been removed by heating, if at all, the apparatus according to Fig. 2 may be employed with advantage. This consists of a (for example) cylindrical steel shaft a, which must be constructed to stand an internal pressure, such as 100 atmospheres (according to circumstances). This steel cylinder is lined with refractory and insulating material, and its interior space is divided, from above downwards, into a hydrogenation zone b, a gasification zone c, and an ashpit d. On top of the steel cylinder is a charging device e for the admission of the fuel. The ashpit d is provided with a discharge outlet f. The charging and discharging apparatus may be designed, in point of detail, in the same manner as in Fig. 1. The hydrogenation zone b is provided with heating appliances g, preferably based on the principle of electrical resistance heating, which raise the fuel in that zone to a suitable temperature for hydrogenation. Oxygen, or air enriched with oxygen, is admitted, in admixture with steam and, on occasion, carbon

dioxide, below the gasification zone *c*, by way of the supply pipe *h*. The gaseous products of gasification are led away from the top of the hydrogenation zone *b*, by way of the pipe *i*, in order to be subjected to further treatment, such as the removal of water vapour, carbon dioxide, condensable hydrocarbons and sulphur compounds. The purified gas is then directly available, under pressure and with a calorific value suitable for urban 10 gas purposes. It may, of course, also be subjected to further transformations, or rendered suitable for chemical purposes, such as ammonia synthesis, or the like. For example, in producing the oxygen needed for the process by compressing 15 air, the nitrogen obtained in that operation may, with particular advantage, be utilized, in association with a portion of the gas from the producer, for the synthetic production of fertilizers.

In order to increase the hydrogenating action, 20 the gas (or a portion of same) produced in the gasification zone *c* may also be led off through the pipe *k*, between the gasification and hydrogenation zones, and freed, in the first place, from steam, carbon dioxide and sulphur compounds. 25 This purified gas, after being heated to hydrogenation temperature, may be passed, through the pipe *i* into the hydrogenation zone. In such case, the hydrogenation products can then be removed from the hydrogenation zone by way of a 30 separate pipe, or else, in association with the gases from the gasification zone, through the pipe *k*. Under these conditions a circulation of part of the gases containing hydrogen, is set up through the hydrogenation zone *b* and the apparatus for 35 the separation of the hydrogenation products, carbon dioxide and sulphur-hydrogen compounds. Nevertheless, the gas from the gasification zone *c* and the gas from the hydrogenation zone *b* may be separately withdrawn from the producer and 40 separately purified.

In the same manner as for the generation of the gas, the hydrogenation reactions may be accelerated by the addition of catalysts or accelerative agents, such as compounds of alkalis, calcium or 45 iron, to the fuel. Particular advantage attaches to the employment of such additions as volatilize at the higher temperatures in the gasification zone and, in an extremely divided condition, are returned, as mist, into the hydrogenation zone, 50 by the resulting gases.

In some cases it is also of advantage to introduce into the hydrogenation zone by-products, phenolates and like substances, from the process itself or from external sources, which can thus 55 be converted into light oils and valuable gases without any additional cost.

The gas produced by the process of the present invention, is already under a high pressure, such as 20 atmospheres, and therefore the steam contained therein condenses, during the cooling and purification of the gas, at a considerably higher temperature than heretofore. Surface or injection condensers may be employed. A steam of medium pressure, which may, for example, be 60 compressed to the gasification pressure and returned to the gas producer, may be suitably generated from the condensate.

If the gas produced in accordance with the invention is to be employed for ammonia synthesis or hydrogenation purposes, it is advantageous to operate so that it will contain as high a proportion of hydrogen as possible. According to the invention, this result is achieved in that, by means of a relatively short reaction period between 70 the gasifying medium and the fuel, (rapid pas-

sage of the gasifying medium through the fuel), the reduction of the carbon dioxide to carbon monoxide is still further restricted, and the combination of the hydrogen and carbon, to form hydrocarbons, is kept down as far as possible. 5 In this manner, a gas consisting of hydrogen and carbon dioxide, to the extent of about 80% can be obtained.

The composition of the gas can, of course, also be influenced, in a desired and already known 10 manner, by incomplete gasification of the fuel, or also by partial removal of the degasified fuel. In the gasification of bituminous fuels, a dry distillation with resulting formation of gas and condensable hydrocarbons takes place in the upper 15 portion of the gas producer, even when no special hydrogenation zone is provided. A coke-like fuel passes into the gasification zone proper. It is not necessarily to gasify all of this fuel. A portion of it 20 may be removed from the producer before the gasification, or the gasification may be so conducted that some carbon is still present in the residue. It is thus possible to raise the content in distillation gases of the final product and consequently, 25 also, to increase the calorific value of the gas.

In gasification with oxygen under ordinary pressure, it has hitherto been the practice to separate the oxygen from air by known processes. In such case the oxygen is obtained under ordinary pressure and has to be compressed to the requisite 30 extent prior to its admission into the gas producer. In certain cases, however, it is preferable to generate the necessary oxygen by the electrolysis of water under pressure, the oxygen 35 being then obtained direct with a pressure which may correspond to the gasification pressure, so that the otherwise essential compression is unnecessary. At the same time, the hydrogen generated under pressure can be employed for enriching the purified gas with hydrogen, or the gas 40 introduced into the hydrogenation zone, or also directly used for the hydrogenation treatment.

The process of the present invention enables a valuable high-power gas to be produced, which 45 has a composition similar to that of coal gas, and the process also furnishes a good yield of light oils at the same time. The yield of light oil is dependent upon the character of the fuel used. Under the same conditions, from two fuels of different 50 bituminous content, in one case 2.3 per cent of light oil was obtained, and in the other case, only 1.1 per cent. The yield of light oil can, however, be substantially increased by raising the pressure, by use of catalysts, and by providing the above-described hydrogenation zone. The plant can be 55 adapted so as to furnish more gas or more oil, according to the state of the market, by varying the working conditions. Although the process directly furnishes a gas of the requisite pressure 60 for remote supply purposes, the only work of compression needed is that for the relatively small quantities of oxygen required in the process.

I claim:—

1. Process of producing a gas having a calorific 65 value at least as high as water-gas which comprises gasifying a solid carbonaceous fuel in the absence of foreign catalytic agents materially affecting the reaction under a pressure greatly in excess of two atmospheres with a gasifying agent consisting essentially of oxygen and steam 70 in such regulated proportions that the gasification temperature is maintained at about 600 to 900° C., whereby a considerable quantity of methane is produced.

2. Process of producing a gas having a calo- 75

- rific value at least as high as water-gas which comprises introducing a mixture comprising a solid carbonaceous fuel and a catalyst into a gasifying chamber and gasifying said fuel therein under a pressure greatly in excess of two atmospheres with a gasifying agent consisting essentially of oxygen and steam in such regulated proportions that the gasification temperature is maintained at about 600 to 900° C., whereby a considerable quantity of methane is produced.
3. Process of producing a gas having a calorific value at least as high as water-gas which comprises gasifying a solid carbonaceous fuel in the absence of foreign catalytic agents materially affecting the reaction under a pressure greatly in excess of two atmospheres with a gasifying agent consisting essentially of oxygen and steam and containing substantially less nitrogen in proportion to oxygen than is present in air, the oxygen and steam being in such regulated proportions that the gasification temperature is maintained at about 600 to 900° C., whereby a considerable quantity of methane is produced.
4. Process as claimed in claim 1 wherein the pressure is at least 15 atmospheres.
5. Process as claimed in claim 1 wherein the pressure is 20 to 50 atmospheres.
6. Process of producing a gas having a calorific value at least as high as water-gas which comprises gasifying a solid carbonaceous fuel in the absence of foreign catalytic agents materially affecting the reaction under a pressure greatly in excess of two atmospheres with a gasifying agent consisting essentially of one part by volume of oxygen and about 6 to 10 parts by volume of steam.
7. Process of producing a gas having a calorific value at least as high as water-gas which comprises introducing a mixture comprising a solid carbonaceous fuel and a catalyst into a gasifying chamber and gasifying said fuel therein under a pressure greatly in excess of two atmospheres with a gasifying agent consisting essentially of one part by volume of oxygen and about 6 to 10 parts by volume of steam.
8. Process of producing a gas having a calorific value at least as high as water-gas which comprises gasifying a solid carbonaceous fuel in the absence of foreign catalytic agents materially affecting the reaction under a pressure greatly in excess of two atmospheres with a gasifying agent consisting essentially of one part by volume of oxygen and about 6 to 10 parts by volume of steam at a temperature of about 600 to 900° C. 5
9. Process as claimed in claim 8 wherein the pressure is at least 15 atmospheres.
10. Process as claimed in claim 8 wherein the pressure is 20 to 50 atmospheres.
11. Process as set forth in claim 1 wherein the fuel is gasified in a state of suspension.
12. Process as claimed in claim 1 wherein the greater portion of the carbon dioxide contained in the gas produced is removed therefrom without substantially lowering its pressure. 15
13. In a process of producing a gas having a calorific value at least as high as water-gas which comprises gasifying a solid carbonaceous fuel in the absence of foreign catalytic agents materially affecting the reaction under a pressure greatly in excess of two atmospheres with a gasifying agent consisting essentially of oxygen and steam in such regulated proportions that the gasification temperature is maintained at about 600-900° C., the gasifying agent being passed through a column of 25 the fuel from the bottom, the steps of withdrawing at least a portion of the hydrogen containing gas from the gasification zone of the column, removing from this gas steam, carbon dioxide and sulfur compounds, heating the same and passing it into 30 intimate contact with the fuel above the gasification zone.
14. In a process of producing a gas having a calorific value at least as high as water-gas which comprises gasifying a solid carbonaceous fuel in 35 the absence of foreign catalytic agents materially affecting the reaction under a pressure greatly in excess of two atmospheres with a gasifying agent consisting essentially of oxygen and steam in such regulated proportions that the gasification temperature is maintained at about 600-900° C., the gasifying agent being passed through a column of the fuel from the bottom, the steps of withdrawing gas at the top of the column of fuel, removing therefrom steam, carbon dioxide and sulfur 40 compounds, heating the purified gas and passing the heated gas into intimate contact with the fuel above the gasification zone. 45

OTTO HUBMANN.
